UNITED STATES PATENT OFFICE.

JOHN J. WILLIAMSON, OF BOSTON, MASSACHUSETTS.

MONEY-ORDER BLANK.

SPECIFICATION forming part of Letters Patent No. 403,499, dated May 14, 1889.

Application filed August 13, 1883. Serial No. 103,686. (No model.)

To all whom it may concern:

Be it known that I, JOHN J. WILLIAMSON, of Boston, in the county of Suffolk and State of Massachusetts, have invented a certain new and useful Improvement in Money-Order Blanks, of which the following is a full, clear, and exact description, reference being had to the accompanying drawings, forming a part of this specification, in explaining its nature.

5 This invention is an improvement on that described in my application of March 11, 1882, and some parts of it are applicable to other forms of money-order, such as express-certificates of deposit, postal-notes or postal-orders, checks, and the like.

10 The example given in the drawings is a money-order postal-card.

Figure 1 represents a card with part of the value-column canceled. Fig. 2 represents a 15 card and its stub uncanceled.

The invention consists in providing one or more peculiar value-columns on the margin of the order, on which the value of the card shall appear plainly in figures, which, when 20 added, shall make the value to be paid at a redemption-office.

25 In a decimal currency—say of dollars and cents, or francs and centimes—the use of one column would indicate a value in cents or of centimes up to one dollar or one franc, the use of two columns would indicate a value in dollars or francs up to one hundred, and the range of the third column would be up to ten thousand dollars or francs, so that by the use 30 of three columns of the same table any value up to ten thousand one hundred and one dollars or francs could be represented. The numbers most convenient for making the 35 columns are 50, 25, 10, 8, 4, 2, 1, whereby any number may be expressed up to 100. Ten Arabic numerals, two 0's, two 1's, two 2's, two 5's, one 4, one 8 make the case for printing this 40 table, while for printing a column of units and tens twenty different types of ten different sorts would be required.

45 The issuer of the card would use it as follows: He knows the table adds up to one hundred, he has money given him to a given amount—say thirty-nine cents—he takes a card and a 50 punch and punches out the numbers 50, 10, and 1, just as if he were making change out

of a dollar, adding the value of the numbers canceled to the sum paid him till he gets to a dollar, and the numbers left when the punching is done when added will make the 55 amount received.

The former tables in use were generally heavy columns of values which proceeded by short stages—say a progression of five cents, from five cents to five dollars, or from one 60 dollar to five dollars, or the like. These last tables would require sixty Arabic figures to each hundred after the first, and for the first hundred thirty-nine Arabic figures; or there have been columns of numbers doubling 65 consecutively from one cent upward, giving an uneven sum differing from the standard of the currency, and thus rendering it troublesome, awkward, and unready to make change. In such case also a large number of figures 70 have been necessary to make the order available for use. It will thus be seen that these particular addition-columns are a new departure in money-order blanks.

In the drawings, *a* is a place for the post-age-stamp.

75 *b* is a legend showing the party responsible for the redemption of the order, which may be the United States postal department or an express-company, a bank, or a private person, 80 as each particular case may be.

c is a space for the address.

85 *d* is the coupon indicating value, and *e* is the stub indicating value.

The stub and coupon being folded together 90 in the usual way with figure columns, as in railroad-blanks, for simultaneous cancellation, the numbers which are not needed for indicating the amount are punched out and the coupon and card torn from the stub and 95 delivered to the purchaser of the money-order. If the card be a postal-card, the message is written upon the reverse side, not covering any part of the money-coupon, and the whole order is presented at the pay-office, 100 and the party paying it removes the coupon as a voucher. In order to show the office from which the coupons have come, they should be stamped either on the front or back of the coupon, so that the accounts may be made correct.

Of course, this money-order cannot be

raised, because only the figures are left on it, which, when added together, make up the amount for which it is an order, and so being stamped upon the back by the issuing office 5 the charge can be entered up against that office.

In case this invention is used as an express money-order or for bankers the place for the postage-stamp will be omitted and the directions may be printed on the back, or an additional blank to be filled up with ink for the amounts could be added for protection. In case it was used in the English "check-bank" system a book of orders would be issued, and 15 on the return of the stub and comparison with the checks received the amount of money not used would be refunded.

I claim as my invention and desire to secure by Letters Patent of the United States—
20 A money-order blank or the like provided

with a margin, upon which is printed a column of figures representing denominations of the currency of the country, as described, the additions of which figures will make the maximum amount for which the order may 25 be drawn, which amount corresponds to a denomination of said currency, and the addition of selections from which, left uncancelled, will make a sum of lesser denomination of said currency, whereby the preparation of the order for the amount desired will be ready and instantaneous, like making change in the accustomed manner, and of the common standard of currency of the country, and the amount for which the order is given 30 35 will be immediately recognizable.

JNO. J. WILLIAMSON.
